CLAIM

The ornamental design for a handheld computer device housing, as shown and described.

DESCRIPTION

FIG. 1 is a front perspective view of a handheld computer device housing, showing the new design; FIG. 2 is a back perspective view thereof; FIG. 3 is a front elevational view thereof; FIG. 4 is a back elevational view thereof; FIG. 5 is a bottom plan view thereof; FIG. 6 is a top plan view thereof; FIG. 7 is a left side elevational view thereof; and, FIG. 8 is a right side elevational view thereof. The broken lines shown in the drawings depict portions of the handheld computer device housing that form no part of the claimed design.

1 Claim, 4 Drawing Sheets
